UNITED STATES PATENT OFFICE.

BENJAMIN F. MALOTT, OF GREENVILLE, SOUTH CAROLINA.

SWING.

1,418,192.

Specification of Letters Patent. Patented May 30, 1922.

Application filed July 23, 1921. Serial No. 487,080.

To all whom it may concern:

Be it known that I, BENJAMIN F. MALOTT, a citizen of the United States, residing at Greenville, in the county of Greenville and 5 State of South Carolina, have invented new and useful Improvements in Swings, of which the following is a specification.

This invention relates to combined benches and swings and has for an object the provision of means whereby the same may be 10 quickly and easily adjusted for either use.

Another object of the invention is the provision of novel means for accomplishing the above, which means includes a reversible 15 back, together with a folding foot rest, the latter also serving as a support, when the invention is used as a bench.

With the above and other objects in view, the invention further includes the following 20 novel features and details of construction, to be hereinafter more fully described, illustrated in the accompanying drawings and pointed out in the appended claim.

In the drawings:

25 Figure 1 is a front elevation of the invention showing the same in use as a swing.

Figure 2 is an end view showing the invention in use as a bench.

Figure 3 is a similar view with the invention 30 in use as a swing, one position of the back and one foot rest being shown by dotted lines.

Figure 4 is a plan view with the invention raised as in Figure 1.

35 Figure 5 is a transverse sectional view with the invention arranged as in Figure 3.

Referring in detail to the drawings, wherein like characters of reference denote corresponding parts, the invention includes 40 a seat 10 and a back 11, which is connected to the seat in a manner hereinafter described.

The seat may be of any desired construction, the one shown including a frame formed of longitudinal bars 12 and trans- 45 verse bars 13, while mounted upon this frame is a plurality of spaced strips 14. The bars 12 of the frame are extended beyond the ends of the strips 14 and have secured thereto uprights 15, whose free ends 50 are connected by arms 17, so as to provide arm rests for the seat.

The back 11 is formed of end bars 18, which are connected by strips 19, a notched cleat 20 being secured to each of the bars 18 55 for receiving the lower edge of the lower-most strip 19.

The lower ends of each of the bars 18 have pivotally secured thereto one end of a link 21, as indicated at 22. The opposite end of this link is pivotally secured to one of the 60 transverse bars 13 of the seat frame. This provides an offset hinged connection between the seat and back and permits of the latter being adjusted to position the same at either longitudinal edge of the seat and thus reverse 65 the position of its use.

In order to limit the pivotal or hinged movement of the back in either direction, the arms 17 are cut away along one side edge intermediate their ends to provide opposite stop shoulders 24 and the bars 18 of the back operate within this cut out portion so as to engage these shoulders. In order to reverse the back, the latter is first raised and then moved transversely of the seat 70 75 until the bars 18 engage the shoulders 24.

The seat is further provided with combined supporting legs and foot rests and for this purpose, there is hingedly secured beneath the seat along the opposite longitudinal edges of the latter, spaced legs 25, the hinged connection between the legs and seat being indicated at 26. The lower ends of these legs are connected by a horizontally disposed brace 27 which in addition to holding the legs properly spaced apart, provides a foot rest. The combined foot rest and brace is connected to its respective legs through the medium of braces 28. Carried by each of the legs 25 is a hook 29 which is 80 85 adapted to engage an eye 30, located adjacent the upper end of each of the legs. This serves to hold the legs in extended position. An additional hook 21 which is secured to one of the transverse bars 13, is receivable 90 within an opening 32 provided in each of the braces 27, so that either of the legs or foot rests, may be held in folded position 95 beneath the seat.

Extending through each of the arms 18 100 near the opposite ends thereof, are eye bolts 33, the said bolts extending downwardly through the ends of the longitudinal bars 12 of the seat frame. These eye bolts provide means of connection with supporting 105 ropes or chains 34, by means of which the swing is suspended. By extending these eye bolts 33 downward through the arms and bars 12, the swing is firmly suspended from its seat.

110 The invention is susceptible of various changes in its form, proportions and minor

details of construction and the right is herein reserved to make such changes as properly fall within the scope of the appended claim.

5 Having described the invention what is claimed is:—

A combined bench and swing comprising a seat, a back secured to the seat, means connected to the seat, whereby the swing 10 may be suspended, means whereby the back

may be reversed, spaced legs hingedly secured beneath each longitudinal edge of the seat, whereby the legs may be folded upward beneath said seat, a combined foot rest and brace connecting the legs and means 15 for holding the legs in folded or unfolded position.

In testimony whereof I affix my signature.

BENJAMIN F. MALOTT.
